PLATE LOCKING CLIP ASSEMBLY

Earl P. Lacure, Battle Creek, Mich., assignor, by
mesne assignments, to Goss Printing Press
Company, Chicago, Ill., a corporation of Illinois

Application June 13, 1946, Serial No. 676,532

17 Claims. (Cl. 101—378)

1

This invention is a novel improvement in plate locking clip assemblies, and the principal object thereof is to provide a simple, novel and efficient plate locking clip assembly for locking a pair of stereotype tubular printing plates onto a printing cylinder, my invention including a novel center clip assembly, end ring assembly, and end clamp assembly, each assembly cooperating with the others to lock the pair of plates onto the cylinder.

Other minor objects of the invention will be 10 hereinafter set forth.

I will explain the invention with reference to the accompanying drawings, which illustrate one practical embodiment thereof to enable others familiar with the art to adopt and use the same; and will summarize in the claims the novel features of construction, and novel combinations of parts, for which protection is desired.

In said drawings:

Figures 1 and 1a show an elevation, partly in section, of a plate cylinder of a printing press or the like provided with my novel center clip assembly, end ring assembly, and end clamp assembly, for locking a pair of stereotype tubular plates thereon.

Fig. 2 is an enlarged detail section through the end ring assembly.

Fig. 3 is an enlarged vertical section through the center clip assembly.

Fig. 4 is a top plan view of the parts shown in Fig. 3.

Fig. 5 is a top plan view of a holding block for a center clip, shown in Figs. 3 and 4, detached.

Fig. 6 is a side elevation of the holding block shown in Fig. 5.

Fig. 7 is a side elevation of an operating block for a center clip shown in Figs. 3 and 4, detached.

Fig. 8 is a top plan view of the operating block shown in Fig. 7.

Fig. 9 is a longitudinal section through a center clip, shown in Figs. 3 and 4, taken on the line 9—9, Fig. 10.

Fig. 10 is an end elevation of the center clip shown in Fig. 9.

Fig. 11 is a bottom plan view of the center clip shown in Fig. 9.

Fig. 12 is an end elevation of the center clip ring.

Fig. 13 is a side elevation of the center clip ring, shown in Fig. 12; and

Fig. 14 is a top plan view of the center clip ring shown in Fig. 12.

As shown in Figures 1 and 1a, the plate cylinder A is adapted to hold a pair of stereotype tubu-

2

lar printing plates B and C, each plate having its ends beveled as at B' and C' respectively.

At one end of cylinder A is an end ring 1 (Figures 1 and 2) making a sliding fit upon said cylinder, ring 1 having its inner end beveled as at 1a to engage the leading beveled end B' of printing plate B. End ring 1 is also provided with a plurality of slots 1b extending longitudinally from its inner end for the purpose hereinafter described.

The outer end of the bore of end ring 1 is enlarged at 1c for the reception of a stop ring 2, the underlapping portion of which is adapted to fill the enlarged portion 1c of the bore of ring 1, said stop ring having at its outer end an internal annular flange 2a adapted to seat in one of a series of annular grooves A', A2 or A3 in cylinder A so as to prevent axial movement of end ring 1 on cylinder A. Stop ring 2 is made

20 in two semi-circular halves so as to be readily insertable and removable from the grooves A', A2 and A3. It is held from removal from the particular groove A', A2 and A3 in which it is inserted by means of the end ring. By placing 25 the stop ring 2 in any of the series of grooves A', A2 or A3, a greater or less number of which may be provided, the position of end ring 1 on the cylinder may be adjusted to take care of different lengths of tubular plates B and C.

30 Extending longitudinally of cylinder A is a keyway A4 (Fig. 1) adapted to receive a key 3 (Fig. 2), said key having an upturned end 3a adapted to contact the outer end of stop ring 2. In order to lock the end ring 1 and the stop ring 35 2 together and to prevent rotation of the rings 1 and 2 around cylinder A, the key 3 is provided with a tapped bore 3b (Fig. 2) receiving a cap screw 4 or the like passing through the end ring 1 and into the threaded bore 3b, the head of the 40 screw 4 seating in an enlarged recess 1d in the outer face of end ring 1 so that no portion of screw 4 projects beyond the periphery of end ring 1. When screw 4 is thus engaged, the rings 1 and 2 as above stated, are locked against rotation 45 around the cylinder A, for the purpose hereinafter described.

Cylinder A is provided adjacent its center with an annular recess A5 (Fig. 1) of substantial depth and width, the recess underlying the adjacent ends of the printing plates B and C, said recess A5 housing the center clip assembly shown more particularly in Figs. 1, 3 and 4. The center clip assembly comprises a center clip ring 5 shown more particularly in Figs. 12, 13 and 14, said ring 55 being substantially cylindrical and made in two

semi-cylindrical halves so as to be readily insertable and removable from recess A5. Ring 5 is made of good steel and hardened so that it will stand wear and abuse and is replaceable if necessary. Ring 5 is of length corresponding to the length of recess A5, and is of internal diameter to suit the reduced diameter of the cylinder in way of recess A5, same having a wall thickness corresponding with the depth of the recess A5. Each half of ring 5 is provided with bores 5a adjacent their ends, as shown more particularly in Figures 12 and 13, for the reception of cap screws (not shown) which pass through the bores 5a and enter threaded bores in the cylinder A to retain the halves in the recess A5. Preferably the outer ends of the bores 5a are enlarged to receive the heads of the anchor bolts so that the heads will not project beyond the periphery of the ring 5.

In the periphery of center clip ring 5 is an annular series of longitudinally disposed guideways, each having outer parallel-walled portions 5b, and inner parallel-walled enlargements 5c, thus forming undercut guide slots, for the purpose hereinafter described. Adjacent the ends of the slots 5b, 5c farthest removed from end ring 1 are a pair of countersunk bores 5d (Figure 14) for the purpose hereinafter described, while at the end of each slot adjacent the end ring 1 is a countersunk bore 5e (Figure 14), said bores 5d, 5e, being disposed axially of slots 5b, 5c and extending radially outwardly through the bases of the guide slots.

Within each of the guide slots is an operating block 6, shown more particularly in Figures 3, 4, 7 and 8, said block 6 being of less depth and width than its related guide slot 5b, 5c and having bores 6a (Figure 3) adapted to receive rivets 7 (Figure 3) which pass through the pair of countersunk bores 5d in the center clip ring 5 and into the bores 6a of blocks 6 to secure the operating blocks 6 in position therein. As shown in Figures 1, 3 and 4, the block is mounted adjacent the end of the guide slots 5b, 5c farthest removed from end ring 1, and each operating block 6 has an upwardly and outwardly inclined portion 6b extending towards the end ring 1, said inclined portions 6b terminating as at 6c (Figures 3 and 7) in a plane parallel with the periphery of cylinder A but below the surface thereof, as clearly shown in Figures 1 and 3.

As shown in Figure 4, each operating block 6 is disposed axially of the guide slot 5b, 5c and is of less width than said slot. Slidably mounted with respect to each operating block 6 is a center clip 8, shown more particularly in Figures 3, 4, 9, 10 and 11, said center clip 8 being of substantially inverted U-shape (Figure 10) providing in its under side a slot 8a of width slightly greater than the width of the operating block 6 upon which the center clip 8 rests, the legs of the clip having enlargements 8b at their lower ends making a sliding fit within the lower wider portion 5c of the guide slot 5b, 5c, permitting the center clips to be shifted radially inwardly within the guide slots from the operative or projected position shown in full lines in Figures 1 and 3, to the retracted position shown in dotted lines in Figure 1. The end of center clip 8 removed from the end ring 1 is provided with a connecting bridge 8c seating upon the end 6c of the operating block 6 when in projected or operative position shown in full lines in Figures 1 and 3, and the inner end of the bridge 8c is beveled upwardly as at 8d on an angle corresponding with the in-

clination of the portion 6b of the operating block 6, the bridge 8c terminating in said inclined portion 8d. The portion of center clip 8 directly above enlargements 8b is of a width and height adapted to make a sliding fit within the outer portion 5b of the guide slot 5b, 5c, and upon the top of bridge 8c is a lug 8e having both ends undercut as at 8f, 8g to engage the adjacent beveled ends B' and C' of printing plates B and C when in operative clamping position. The locking lug 8e has its outer face formed arcuately to conform with the curvature of the cylinder A; and preferably the ends of the locking lug 8e project sideways beyond the sides of the bridge 8c, as shown more particularly in Figure 10 to increase the width of the plate gripping face of the lug.

In order that the center clip 8 may be projected out of its guide slot 5b, 5c, the walls of the outer portions 5b of the slot are increased in width, as at 5g (Figures 13 and 14) to permit the sidewise extending ends of lug 8e to pass into and out of the guide slot when the center clip is actuated as hereinafter described.

In order that the undercut edges 8f, 8g of the center clip 8 may better grip the beveled ends B', C' of the plates B and C, I preferably provide pins 9 which are passed upwardly through bores 8h in the bridge 8c of the center clip, the bores having their axes substantially bisecting the angles at the lower inner ends of beveled portions 8f, 8g, so that the projecting sides of pins 9 will form locking lugs to enter into and grip the soft metal of the beveled ends B', C' of the stereotype plates, and thereby offset any tendency of the plates B and C to shift laterally with respect to the locking lugs 8e, and to prevent any tendency of the plates B and C to rotate on the cylinder A under operating conditions.

The end of the center clip 8 adjacent end ring 1 is preferably extended beyond the bridge 8c in the form of parallel side walls, and between the said walls is mounted a block 10 shown in Figures 1, 3 and 4, said block being secured by pins or the like 10a, 10b between the parallel walls of center clip 8. The upper face of block 10 is beveled downwardly as at 10c (Figure 3) at an angle conforming with that of the beveled end 8d of bridge 8c and the slope of the under side of the inclined portion 6b of the operating block 6, block 10 thus forming a part of the center clip 8 and moving therewith.

Block 10 is provided on its outer end with an ear 10d which is perforated as at 10e (Figure 4) for pivotal connection with an operating rod 11 for the center clip, said rod 11 having an ear 11a, Figure 4, which is perforated as at 11b, a pair of links 12, connecting ears 11a and 10d, with pins 13 and 14 passing through the links and through the perforated ears, thus causing the center clip to move axially of the guide slot when rod 11 is actuated while permitting the clip 8 to shift vertically within the slot 5b, 5c, and enlargement 5g.

As shown in Figure 3, the distance between the inclined surfaces 10c and 8d of the clip 8 is slightly greater than the thickness of the inclined portion 6b of the operating block 6. Thus, in the position shown in Figure 3, bridge 8c of the center clip is resting upon the horizontal outer end portion 6c of the operating block 6 and in such position the lug 8e is projected through enlargement 5g out of the guideway 5b, 5c, into plate-engaging position. When, however, the operating rod 11 is moved to the right (Figures 1 and 3) the center clip 8 will be shifted therewith until the under side of the bridge 8c passes beyond

the far end of the horizontal portion 6c of operating block 6, whereupon the center clip 8 will be guided by sliding contact of the inclined surface 10c and 8d down the inclined portion 6b of operating block 6 into the retracted position shown in dotted lines in Figure 1, at which time the top of locking lug 8e will have passed wholly into enlargement 5g and will be housed wholly below the surface of the cylinder A.

Within each guide slot 5b, 5c at the end adjacent the operating rod 11 is a holding block 15, shown more particularly in Figures 1, 3, 5 and 6, the same being of width to seat in the lower widened portion 5c of the guide slot and being secured therein by means of a rivet 16 (Figure 3) passing through the countersunk bore 5e in the end of the guide slot and into a bore 15a in the block, said block having a downwardly inclined central portion 15b adapted to be slidably engaged by the under side of the block 10 when the center clip is shifted towards the right (Figure 3). Holding block 15 forms a support for the adjacent end of center clip 8 when the latter is in projected plate-holding position, as shown in Figure 3.

Operating rod 11 is adapted to be actuated by the leading edge of the plate B when inserted from the end of the cylinder A opposite from end ring 1 into its proper position on the cylinder A. For this purpose each rod 11 is housed in a corresponding longitudinal slot A6 (Figure 1) in the periphery of cylinder A offset from the keyway A4 for key 3, hereinbefore referred to, and each operating rod 11 extends beyond the leading end B' of the plate B and beyond the end ring 1 and stop ring 2, and is provided with a series of tapped bores 11c, as shown in Figure 1, opposite the leading edge of plate B into any one of which an Allen set screw 16x is adapted to be placed, said set screw 16x being inserted through the slot 11b, hereinbefore referred to, in the end ring 1 as shown in Figure 1. Thus the set screw 16x may be adjusted on the operating rod 11 to conform with different lengths of plates B. Operating rod 11 is slotted adjacent the collar 5 as at 11d (Figure 1) and a screw 17 (Figure 1) is passed through the slot 11d and is tapped into a threaded bore in cylinder A, screw 17 serving to guide the inner end of the operating rod 11 while permitting axial movement of the operating rod 11 in its groove A6.

The center clip assembly operates as follows:

The Allen set screw 16x is first adjusted in one of the tapped holes 11c in accordance with the length of the particular plate B. Before the plate B is slipped on the cylinder the operating rod 11 would be moved to the right (Fig. 1) its maximum extent so as to retract the center clip 8 below the periphery of the cylinder A. The plate B would then be slipped over the end of the cylinder opposite from the end ring 1 and slid towards the end ring assembly 1 and 2, which latter has previously been properly located in grooves A', A2, or A3 with respect to the length of the plate B. As the leading edge B' of the plate B engages the Allen screw 16x the operating rod 11 will be shifted thereby so that when the leading edge B' engages the end ring 1, as shown in Fig. 1, the center clip 8 will have been shifted therewith from the dotted-line position shown in Fig. 1 to the full-line position shown in Fig. 1 in which latter position the lug 8e is projected into position to engage the trailing end B' of plate B but is spaced therefrom until the end clamp assembly (hereinafter de-

scribed) is actuated at the opposite end of the cylinder. The center clip 8 moving about 1 1/8" lengthwise of the cylinder moves to the top of the operating block 6 and then travels horizontally in the slot 5b, 5c the remaining distance into gripping position between the two printing plates. The plate C would then be slipped over the same end of the cylinder into the position shown in Fig. 1 in which its leading edge C' engages the beveled edge 8g of center clip 8 since the clip 8 has been raised into operative position by the plate B previously placed upon the cylinder A.

The length of the slot 1b in end ring 1 permits the rod 11 to be further shifted to the left (Fig. 1) while the end clip assembly at the opposite end of the cylinder is being actuated to securely lock the plates B and C on the cylinder.

The end clip assembly at the opposite end of the cylinder A is illustrated in Fig. 1a, and as shown that end of the cylinder is reduced in diameter as at A7, the reduced portion extending under the trailing edge C' of plate C, forming a shoulder A8 against which is placed a spacer ring 20 which bears squarely against the shoulder A8. Spacer ring 20 has a bore conforming with that of the reduced portion A7 of the cylinder and an external diameter conforming with that of the main body of cylinder A. Spacer ring 20 has an annular series of bores 20a adjacent the periphery thereof forming journals for the inner ends of plate clamp screws 21 which have reduced cylindrical ends 21a journaled in the bores 20a.

Upon the reduced portion A7 beyond the spacer ring 20 is a plate clamp ring 22 of length to extend beyond the trailing end of plate C, clamp ring 22 having a bore slidably fitting the reduced portion A7 of cylinder A and having an external diameter slightly less than that of the main body of cylinder A. Plate clamp ring 22 is provided with longitudinally disposed peripheral slots 22a in which the plate clamp screws 21 are housed, and plate clamp ring 22 is secured to the cylinder A by means of bolts 23 having heads 23a disposed in bores 22c extending inwardly from the outer end of ring 22, said bolts being threaded into tapped bores A9 in the shoulder A8 of the cylinder A, whereby the plate clamp ring 22 is securely mounted on the cylinder preventing same from axial or rotary movement thereon.

At the outer end of the plate clamp ring 22 is an end plate 24 of less diameter than the cylinder A, said end plate 24 being secured to ring 22 or cylinder A in any desired manner, said end plate 24 having bearings 24a for the outer ends of the plate clamp screws 21, said screws having collars 21b engaging the end plate 24 to prevent axial movement of the screws 21. The outer ends of the screws 21 extend through the end plate 24 and are provided with non-circular outer ends 21c for engagement with a wrench or the like, whereby the screws 21 may be readily rotated.

Within each slot 22a in the plate clamp ring 22 is a plate clamp 25 threaded upon the related operating screw 21 and having an undercut locking lug 25a adapted to engage the trailing end C' of plate C, the locking lug 25a when in the operative position shown in Fig. 1a projecting out of the slot 22a and hence above the diameter of the major portion of cylinder A. Each slot 22a has at its outer ends a recess 22d (Fig. 1a) of such depth that when the screw 21 is rotated to bring the clamp 25 opposite the recess 22d, the clamp may be rotated on the screw so as to bring the locking lug 25a within the recess 22d, in which po-

sition no portion of the clamp 25 or operating screw will lie beyond the periphery of the major portion of the cylinder A, whereby the plates B and C may be slipped over the end clamp assembly.

Obviously, when the screw 21 is rotated to shift the clamp 25 towards the plate C, the plates B and C with the interposed center clips 8 will be shifted to bring the leading edge B' of plate B into firm engagement with the end ring 1 at the opposite end of the cylinder and the parts will be securely locked in position.

While I have illustrated but one of the center clips 8 with its operating rod 11, and only one of the end clamps 25 with its operating mechanism, obviously as many clamps and clips may be provided in an annular series as may be desired around the periphery of the cylinder, each of the said assemblies operating in the same manner herein described.

I do not limit my invention to the exact form shown in the drawings, for obviously changes may be made therein within the scope of the claims.

I claim:

1. Means for locking a pair of substantially tubular printing plates or the like onto a cylinder, comprising an end ring assembly including an end ring adapted to engage the leading edge of the first plate, said ring being mounted adjacent one end of the cylinder and adapted to be locked in adjusted position thereon; a center clip assembly including center clips disposed between adjacent edges of the first and second plates adapted to be projected beyond the periphery of the cylinder and then parallel to same when in operative position and to be retracted within the periphery of the cylinder in another position thereof; means for projecting the center clips actuated by the placing of the first plate on the cylinder into substantially normal position; and an end clamp assembly at the opposite end of the cylinder including a grooved sleeve with end clamps in the grooves adapted to engage the trailing edge of the second plate and adapted to be shifted to compress the pair of plates with the interposed center clips together and against the end ring.

2. In means as set forth in claim 1, said end ring being disposed around the cylinder and having an enlarged internal recess in its outer end; said end ring assembly also including a pair of semi-circular stop ring sections adapted to fill the enlarged recess in the end ring and to encircle the cylinder, said stop ring sections having internal annular shoulders adapted to engage one of a series of spaced annular grooves in the cylinder.

3. In means as set forth in claim 1, said end ring being disposed around the cylinder and having an enlarged internal recess in its outer end; said end ring assembly also including a pair of semi-circular stop ring sections adapted to fill the enlarged recess in the end ring and to encircle the cylinder, said stop ring sections having internal annular shoulders adapted to engage one of a series of spaced annular grooves in the cylinder; said cylinder having a longitudinal keyway under said end ring assembly; a key in said keyway underlying the end ring and stop ring, said key having an upturned flange contacting the outer face of the stop ring; and a screw transfixing the end ring and the said key.

4. In means as set forth in claim 1, said center clip assembly comprising a pair of collar sections secured in an annular recess in the cylinder underlying the adjacent ends of the pair of plates; said collar sections having longitudinal guidways

in their peripheries provided with enlargements at their lower ends; operating blocks of less width, depth, and length than the guideways axially mounted within the slots at the ends thereof removed from the end ring, said blocks each having outwardly inclined portions extending towards the end rings; and said center clips having slots in their lower ends seating upon the upper faces of the inclined portions of their related blocks and having portions adapted to engage the undersides of the said inclined portions of the operating blocks.

5. In means as set forth in claim 1, said projecting means comprising rods housed in longitudinal peripheral slots in the cylinder, said rods each having one end pivotally connected with their related center clip and its other end adapted to be engaged by the leading edge of the first plate, whereby movement of said plate will shift the center clips from retracted position into projected position when the first plate is shifted into substantially normal position on the cylinder.

6. In means as set forth in claim 1, said center clip assembly comprising a pair of collar sections secured in an annular recess in the cylinder underlying the adjacent ends of the pair of plates; said collar sections having longitudinal guideways in their peripheries provided with enlargements at their lower ends; operating blocks of less width, depth, and length than the guideways axially mounted within the slots at the ends thereof removed from the end ring, said blocks each having outwardly inclined portions extending towards the end rings; said center clips having slots in their lower ends seating upon the upper faces of the inclined portions of their related blocks and having portions adapted to engage the undersides of the said inclined portions; and said projecting means comprising rods housed in slots in the cylinder, said rods each having one end pivotally connected with their related center clip and its other end adapted to be engaged by the leading edge of the first plate, whereby movement of said plate will shift the center clips from retracted position into projected position when the first plate is shifted into substantially normal position on the cylinder.

7. In means as set forth in claim 1, the end of the cylinder in way of the end clamp assembly being reduced in diameter; and said end clamp assembly also including a plate clamp ring on the reduced end underlying the trailing end of the second plate and having longitudinally disposed slots in its periphery, said slots having recesses at their outer ends; means for securing the clamp ring to the cylinder; screw shafts journaled in bearings in each of the slots; said end clamps being mounted on said screw shafts and having lugs adapted to engage the trailing edge of the second plate; and said end clamps being rotatable on the screw shafts, whereby when positioned above the recesses the lugs may be retracted therein so as to lie within the periphery of the cylinder.

8. In means as set forth in claim 1, the end of the cylinder in way of the end clamp assembly being reduced in diameter; and said end clamp assembly also including a spacer collar on the reduced end within the trailing end of the second plate and provided with an annular series of bores adjacent its periphery; a plate clamp ring on the reduced end beyond the spacer collar and underlying the trailing end of the second plate and having longitudinally disposed slots in its periphery aligned with said bores in the spacer collar, said slots having recesses at their outer ends; an end

9

plate on the reduced end beyond the clamp ring having bores aligned with the slots; means for securing the spacer collar, clamp ring, and end plate to the cylinder; screw shafts in each of the slots journaled in the bores in the spacer collar and end plate; said end clamps being mounted on said screw shafts and having lugs adapted to engage the trailing edge of the second plate; and said end clamps being rotatable on the screw shafts, whereby when positioned above the recesses the lugs may be retracted therein so as to lie within the periphery of the cylinder.

9. A center clip assembly for locking a pair of substantially tubular printing plates or the like onto a cylinder, comprising longitudinal guideways in the cylinder periphery underlying the adjacent ends of the pair of plates, said guideways having enlargements at their lower ends; operating blocks of less width, depth, and length than the guideways axially mounted within the slots at the ends, said blocks having outwardly inclined portions extending in the direction of movement of the first plate into position onto the cylinder; and center clips in said guideways having slots in their lower ends seating upon the upper faces of the inclined portions of their related blocks and having portions adapted to engage the undersides of the said inclined portions; and means for shifting the clips axially of the guideways.

10. In an assembly as set forth in claim 9, said center clips having transverse locking lugs on their upper faces of greater width than the outer portions of the guideways; and the walls of the guideways being recessed in way of the lugs to permit the lugs to pass into and out of the guideways.

11. In an assembly as set forth in claim 9, said center clips having transverse locking lugs on their upper faces undercut to engage the adjacent ends of the pair of plates; and pins mounted in bores in the lugs disposed substantially normal to the surface of the cylinder at substantially the lower ends of said undercut portions and adapted to enter into the metal of the plates when clamped by the lugs.

12. In an assembly as set forth in claim 9, the upper ends of the outwardly inclined portions of the operating blocks terminating in planes parallel with but below the periphery of the cylinder, thereby permitting horizontal movement of the clips in the guideways after being projected into operative position out of the guideways.

13. A center clip assembly for locking a pair of substantially tubular printing plates or the like onto a cylinder, comprising a pair of collar sections secured in an annular recess in the cylinder underlying the adjacent ends of the pair of plates; said collar sections having longitudinal guideways in their peripheries, said guideways being provided with enlargements at their inner portions; operating blocks of less width, depth, and length than the guideways axially mounted within the slots at the ends, said blocks having outwardly inclined portions extending in the direction of movement of the first plate into position onto the cylinder; and center clips in said guideways having slots in their lower ends seating upon the upper faces of the inclined portions of their related blocks and having portions adapted to engage the undersides of the said inclined portions; and means for shifting the clips axially of the guideways.

14. In means for locking a pair of substantially

10

tubular printing plates onto a cylinder, comprising an end ring on the cylinder adjacent one end thereof adapted to be engaged by the leading edge of the first plate; a center clip assembly including center clips disposed between adjacent edges of the pair of plates adapted to be projected beyond the periphery of the cylinder and the parallel to same when in operative position and to be retracted within the periphery of the cylinder in another position thereof; and means for projecting the center clips actuated by the placing of the first plate on the cylinder into substantially normal position.

15. In means as set forth in claim 14, said projecting means comprising rods housed in longitudinal peripheral slots in the cylinder, said rods each having one end pivotally connected with their related center clip and its other end adapted to be engaged by the leading edge of the first plate, whereby movement of said plate will shift the center clips from retracted position into projected position when the first plate is shifted into substantially normal position on the cylinder.

16. In means as set forth in claim 14, said end ring having longitudinal slots in its plate engaging edge; and said projecting means comprising rods housed in longitudinal slots in the cylinder below the slots in the end ring, said rods each having one end pivotally connected with its related center clip and its other end underlying the end ring, a set screw insertable into one of a series of tapped bores in the rod underlying the end ring and leading edge of the first plate, said set screw being adapted to be engaged by the leading edge of the first plate, whereby movement of said plate will shift the center clip from retracted position into projected position when the first plate is shifted into substantially normal position on the cylinder.

17. An end clamp assembly for locking a tubular printing plate onto a cylinder having a reduced end, comprising a spacer collar on the reduced end within the trailing end of the plate and provided with an annular series of bores adjacent its periphery; a plate clamp ring on the reduced end beyond the spacer collar and underlying the trailing end of the second plate and having longitudinally disposed slots in its periphery aligned with said bores in the spacer collar, said slots having recesses at their outer ends; and end plate on the reduced end beyond the clamp ring having bores aligned with the slots; means for securing the spacer collar, clamp ring, and end plate to the cylinder; screw shafts in each of the slots journaled in the bores in the spacer collar and end plate; and end clamps mounted on said screw shafts and having lugs adapted to engage the trailing edge of the plate; and said end clamps being rotatable on the screw shafts whereby when positioned above the recesses the lug may be retracted therein so as to lie within the periphery of the cylinder.

EARL P. LACURE.
